(57) **CLAIM**

(21) Appl. No.: **29/328,659**

The ornamental design for a LED spot light, as shown.

(22) Filed: **Nov. 28, 2008**

(30) **Foreign Application Priority Data**

May 28, 2008 (CN) 2008 3 0124097

DESCRIPTION

(51) **LOC (9) Cl.** **26-04**
(52) **U.S. Cl.** **D26/2**
(58) **Field of Classification Search** D26/1-4;
313/313, 315, 317, 318, 493; 315/52, 53,
315/56, 57, 58

FIG. 1 is a front elevational view of a LED spot light showing our new design;

See application file for complete search history.

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.
